UNITED STATES PATENT OFFICE.

EDITH HEBERLEIN, OF OCEANPARK, CALIFORNIA.

LIFE-SAVING GARMENT.

1,098,110.

Specification of Letters Patent. Patented May 26, 1914.

Application filed May 8, 1912. Serial No. 696,086.

To all whom it may concern:

Be it known that I, EDITH HEBERLEIN, a subject of the King of Great Britain, having married a subject of the Emperor of 5 Germany, at present residing at Oceanpark, in the county of Los Angeles and State of California, have invented a new and useful Life-Saving Garment, of which the following is a specification.

10 The object of this invention is to provide for persons on sea-going vessels a garment which will protect them from exposure in case of ship-wreck.

15 A further object is to provide comfortable means to assist in supporting the person of the wearer in the water.

20 Another object is to provide a one piece garment having a large opening at the neck for the insertion of the entire person, the opening being adapted to be quickly and tightly closed when the person is incased in the garment, and the closure being such as to maximize the difficulty with which 25 water may enter the garment.

25 The accompanying drawings illustrate the invention.

Figure 1 is a view of a garment constructed in accordance with this invention and open ready to receive the person to be protected thereby. Fig. 2 is a fragmental view showing the garment as it appears when closed upon the person of the wearer. Fig. 3 is a plan section on line $\alpha\beta$, Fig. 2. Fig. 4 is an exaggerated fragmental section of 35 a portion of the body of the garment.

The garment comprises a structure composed of body 1, legs 2, feet 3, arms 4, gloves 5 and hood 6, made as one piece, the hood being provided with a front opening 7 and 40 the body being provided below such front opening with a foldable unslit fullness 8 extending substantially to the waist, the upper margin 9 thereof being extensible to form, with the margin of the hood, a 45 tensible opening through which the body of the wearer may pass in adjusting the garment to the person. Suitable fastening means, as the strap 10, having a buckle 11 is provided at the neck 12 of the garment to 50 hold the opening closed when the foldable fullness 8 has been folded in place, as shown in Figs. 2 and 3, and a draw-string 13 is run in the usual manner through certain retaining means, as the hem 14, around 55 the margin of the hood opening so that said

opening may be contracted to closely fit the face of the wearer.

From the foregoing it is seen that the garment is unslit from the neck down and is provided at the front with an unslit fullness extending from the lower margins of the hood opening substantially to the waist and adapted to expand to form an opening in front of the hood at the neck and in conjunction with said hood opening to admit the wearer so that when the margins of the hood opening are tightened along the face by means of the draw string 13 and the fullness has been folded and fastened in place by the strap and buckle 10, 11, the garment 60 will afford maximum protection against ingress of water for the reason that when closed the lower margins of the opening 7 are drawn together, as shown in Fig. 2, over the upper margin of the fullness folded beneath the hood; and this security against ingress of water is in nowise diminished by a construction which maximizes the ease with which the garment may be donned.

The garment is made of an outside light-weight water-proof material 15 and an inside light-weight heat-insulating material 16, as flannel, so that by means of the outer thickness 15 the lining 16 and the garments of the wearer are protected from water. 85 The garment is intended to be of sufficient size to be drawn on over the ordinary clothing of the wearer, the leather boots, however, being preferably taken off before the garment is put on. When the garment has 90 thus been put on and secured at the neck, as shown in Fig. 2, the wearer will apply, in the usual manner, a life belt, not shown, so that if he is thrown or jumps into the water he will be supported. In addition to the 95 buoyancy of the life belt, the air confined in his clothing will assist in supporting the body for the reason that the water being excluded from the inside of the garment will not force out the air which is inmeshed in the material of the ordinary clothing worn by the person putting on the garment.

100 It is understood that there is no limitation on the thickness of the material, care being taken that the weight is not excessive and that the foldable fullness shall not be of excessive bulk.

105 By constructing the one piece garment with my particular foldable fullness and integral hood having a draw string, the folds 110

of the fullness may be disposed and secured in such manner as to maximize the difficulty with which water may leak through same into the garment. In fastening the 5 neck piece the fullness 9 is first folded and tucked neatly around the neck as in Fig. 3, after which the strings 13 are drawn, serving at the same time to bind the edge of the hood onto the face, and also to the sides of 10 the neck together and over the upper edge of the folded and tucked fullness as in Fig. 2. The strings 13 alone would serve to seal the opening through edge 9 of the fullness when so lapped beneath the draw string 13 15 of the hood, but to make the seal proof against accidental derangement of the folds the binding strap 10 is provided. This makes a practically perfect seal.

I claim:—

20 A garment of the character set forth comprising body, legs, feet, arms, gloves, and hood, made as one piece and unslit below

the hood, said hood having a front opening and said body being provided at the front with an unslit fullness extending from the 25 lower margins of said hood opening substantially to the waist and adapted to expand to form an opening in front of the hood at the neck and in conjunction with said hood opening to admit the wearer, 30 means to hold the unslit fullness from expanding, and means to tighten the margins of the hood opening around the face of the wearer, the lower margins of the hood opening being adapted to be drawn together over 35 the upper margin of said fullness.

In testimony whereof, I have hereunto set my hand at Los Angeles, California, this 2nd day of May, 1912.

EDITH HEBE FLEIN.

In presence of—

JAMES R. TOWNSEND,
DAISY MUNRO.
